UNITED STATES PATENT OFFICE.

JAMES A. DUFFY AND ALONZO BALL, OF BOYLESTON, ASSIGNEES OF ONE-
THIRD TO PHINEAS BALL, OF WORCESTER, MASSACHUSETTS.

WEAVER'S COMBINED COMB AND REED-HOOK.

SPECIFICATION forming part of Letters Patent No. 341,562, dated May 11, 1886.

Application filed September 21, 1885. Serial No. 177,676. (No model.)

To all whom it may concern:

Be it known that we, JAMES A. DUFFY and ALONZO BALL, citizens of the United States, and both residing at Boylston, in the county of Worcester and State of Massachusetts, have invented certain new and useful Improvements in Weaver's Combined Comb and Reed-Hook; and we declare the following to be a description of our said invention, sufficiently full, clear, and exact to enable others skilled in the art to which it appertains to make and use the same, reference being had to the accompanying drawings, which form a part of this specification.

15 The object of our present invention is to provide a convenient and serviceable pocket-instrument for weavers, for use in drawing threads through heddle eyes and reeds, and for combing out improperly-woven threads 20 and misspicks in the cloth; and our invention consists in the combined instrument herein described, containing a pick-comb and reed-hook, in connection with a pocket-handle, the parts being constructed and arranged for opening and shutting in the manner hereinafter 25 explained.

In the drawings, Figure 1 is a side view of our combined weaver's comb and reed-hook, shown closed, as for carrying in the pocket. 30 Fig. 2 is a front edge view of the same. Fig. 3 is a side view, opposite to that of Fig. 1, shown with the comb open, or swung out in position for use. Fig. 4 is a side view with the reed-hook open, or swung out in position 35 for use, and the comb closed. Fig. 5 is a back edge view of the same; and Fig. 6 is a transverse section at line xx , Fig. 3, on an enlarged scale.

In reference to parts, A denotes the handle, 40 which is in the present instance composed of the sides a a' , and spring-back b , and spring-plate c , which parts are secured together by suitable screws, pins, or rivets, d d' , in the manner illustrated.

45 E indicates a comb, formed of steel or other suitable material, with sharp-pointed teeth, and arranged in a cavity or chamber along one side of the handle A, as indicated. Said comb is provided with journals or pivots e at

its ends, by means of which it is secured to the handle, and on which the comb can turn as a hinge, so as to swing the teeth thereof out to the position shown in Fig. 3, or dotted lines, Fig. 6. The plate c , which is slotted transversely—as at dotted lines c' , Fig. 3—acts 55 as a spring for retaining the comb at positions of adjustment either when opened or closed. A shoulder or rib, f , is arranged along the side of the comb, to serve as a step and brace against the edge of the plate c when the comb 60 is open. A recess, m , is formed in the handle, to allow the thumb-nail to enter behind the comb-teeth, to facilitate opening it when required for use.

A reed-hook, I, made as a flat curved prong, 65 is fitted and hinged at d' in the end of the handle A, in manner similar to the hinging of a pocket-knife blade, or so as to be opened and closed at will. The extension of the prong I is made of a size that can be passed 70 between the dents of a reed, or through heddle-eyes, and said hook is furnished at its end with an open eye, notch, or recess, i , whereby to seize the thread or yarn for drawing it through the reed or heddles.

75 By constructing the weaver's comb and hook in the manner set forth, with said comb arranged to close into a side cavity in a pocket-handle, a very convenient and desirable article is produced, which is simple of construction, and may be manufactured with practical economy and at small cost. The style and form of handle can be made more or less ornamental, as desired.

We are aware that a combined reed-hook and 80 picking-comb has been heretofore patented, and we do not, therefore, herein broadly claim such an article irrespective of its peculiar construction; neither do we claim novelty in the combining of a comb and hook as a pocket-instrument.

85 What we claim as of our invention, and desire to secure by Letters Patent, is—

1. The weaver's combined comb and reed-hook hereinbefore described, consisting of 90 the handle A, having an internal longitudinal space, with the hook I pivoted in the end thereof, and provided with the comb E, dis-

posed upon the side of said handle and pivoted thereto, so as to swing outward and backward laterally about a longitudinal axis, substantially as described.

5. 2. The comb E, having a longitudinal shoulder, *f*, and provided with pivots *e* at its ends, in combination with the handle A, having a side cavity to receive said comb, a central longitudinal space, and the intervening plate *c*,

provided with transverse slits *c*², substantially as and for the purpose set forth.

Witness our hands this 7th day of September, A. D. 1885.

JAMES A. DUFFY.
ALONZO BALL.
